UNITED STATES PATENT OFFICE

FREDERICK A. VASTANO, OF PATERSON, NEW JERSEY

ENGINE STARTER

Application filed March 22, 1932. Serial No. 600,441.

This invention relates to starting mechanism for internal combustion engines, and particularly to starting mechanism to be used in connection with internal combustion engines employed in the so-called "kicker" or propelling means for small boats. The principal object is to provide, in combination with the fly-wheel or equivalent rotary element of such an engine, a starting mechanism in which the power may be stored up by hand and then readily released for starting the engine. Another object is so to construct the starting mechanism that it may be readily applied to said element and then removed when the engine has been started, being for that purpose as compact and light in weight as possible. Another object is to construct the part of said mechanism whereby the power is manually stored up so as to afford an effective grip to the operator and a convenient means for applying the mechanism to or removing it from said element.

In the drawing,

Fig. 1 is a side elevation, partly in section, showing the fly-wheel and timing disk of the engine and my starter mechanism operatively associated therewith;

Fig. 2 is a plan thereof;

Fig. 3 is a fragmentary side elevation of the spring-drum and fly-wheel;

Fig. 4 shows a modification of the handle; and

Fig. 5 shows an adapter by which the engine shaft may be extended if necessary to accommodate my mechanism.

In the drawing, 1 is the projecting shaft and 2 the fly-wheel or equivalent rotary element of the engine, and 3 is a part of the engine, as its timing disk, with reference to which the fly-wheel rotates.

On the shaft is arranged a handle structure comprising a sleeve 4 and the handle 5. The sleeve is revolute on the shaft and has a lower flange 4a, an upper flange 4c screwed onto its threaded portion 4b, and a square head 4d upon which is fitted the square central socket of the handle 5, which is here in the form of a wheel.

The flanges 4a and 4c form with flanges 6a

of a hollow drum 6 the races for the balls 7 of ball-bearings.

Contained in the drum and secured at its ends thereto and to the sleeve of the handle structure is a helical spring 8.

On the top of the drum is a series of ratchet teeth 9 concentric therewith, and arranged in a radial housing 5a of the handle structure is a pawl 10 normally held engaged with said ratchet teeth by a spring 11, said pawl being adapted to be withdrawn from the ratchet teeth by a grip in the form of a lever 12 which is connected with the pawl by a link 13 and has its grip-portion 12a underlying the annular handle or grip portion of the wheel 5.

The mechanism comprising the sleeve, drum and spring is unitary in character, and if the handle is pinned, as at 5x, to the sleeve it will form a part of such unitary mechanism. Such mechanism is adapted to be placed on or removed from the shaft, for which purpose the wheel 5 forms a convenient means for lifting it with the use of both hands.

On the lower face of the drum are ratchet teeth and on the top face of the element 2 other ratchet teeth, both arranged concentrically of the shaft and coactive with each other. These teeth form abutments coactive with each other to resist rotation of the drum relatively to said element when the handle structure is rotated in the direction in which the pawl 10 clicks idly over the teeth 9 and formed to cam past each other when said element is rotated in said direction by engine power, as when the engine has been started. Thus the acting and camming faces 14a and 15a, respectively, are faced reversely to the corresponding faces of the teeth 9.

At 16 is a locking pin or detent removably arranged in holes 1a and 3a of the drum and part 3.

Instead of the wheel 5 the handle may take the form of a lever 17 as shown in Fig. 4.

Operation.—The parts being assembled as shown in Fig. 1, so that the ratchet teeth 14—15 prevent the drum from rotating in the direction of winding up the spring (or here clockwise), the handle structure 4—5 is rotated by hand in said direction, thus winding

the spring, said structure being held from re-
rotation, thus to preserve the spring energy
stored up, by the engagement of pawl 10 with
ratchet 9. If the resistance in the engine is
not sufficient to prevent the fly-wheel from
rotating in this operation pin 16 may be ap-
plied to lock the fly-wheel to the timing disk
3. Having thus stored up power in the
spring (and having removed pin 16 if it has
been made to lock the fly-wheel and timing
disk together), and while now manually
holding said structure from re-rotation the
operator retracts the pawl 10 by pressure on
lever 12, whereupon the energy of the spring
will be freed to rotate the fly-wheel and hence
start the engine, the abutments 14-15 click-
ing idly past each other. The unit 4-6-8
may now be removed, and if the handle 5 is
a part thereof it will form a convenient means
for lifting it.

If the shaft 1 is not upwardly prolonged
far enough to form a proper support for the
sleeve 4 the extension or adapter 18 shown in
Fig. 5 may be screwed onto its upper end.

Having thus fully described my invention
what I claim is:

1. In combination, with the rotary element
of an internal combustion engine, said ele-
ment having a projecting axial shaft, a unitary
starting mechanism for the engine com-
prising a handle structure having a sleeve to
fit over and revolve upon the shaft, a drum
revoluble on the sleeve and a helical spring
in the drum connected at its ends to the drum
and sleeve, said drum having ratchet
teeth concentric with the sleeve, and a
manually disengageable pawl normally en-
gaged with said teeth and carried by the
handle structure, said element and drum hav-
ing coactive abutments adapted to resist rota-
tion of the drum relatively to said element
when the handle structure is rotated in the
direction in which the pawl clicks idly over
said ratchet teeth and formed to cam past
each other when said element is rotated in
said direction under engine power.

2. In combination, with the rotary element
of an internal combustion engine, said ele-
ment having a projecting shaft, a unitary
starting mechanism for the engine com-
prising a handle structure having a sleeve to fit
over and revolve upon the shaft and a handle
remote from the sleeve, a drum revoluble on
the sleeve and a helical spring in the drum
connected at its ends to the drum and sleeve,
said drum having ratchet teeth concentric
with the sleeve, a pawl device normally en-
gaged with said teeth and carried by the
handle structure and having a manually oper-
ated grip adjacent the handle of the latter,
said element and drum having coactive abu-
ments adapted to resist rotation of the drum
relatively to said element when the handle
structure is rotated in the direction in which
the pawl clicks idly over said ratchet teeth

and formed to cam past each other when said
element rotates in said direction under engine
power.

3. In combination, with the rotary element
of an internal combustion engine, said ele-
ment having a projecting shaft, a unitary
starting mechanism for the engine comprising,
with a handle structure itself comprising
a sleeve to fit over and revolve upon the
shaft and a handle fixed against axial dis-
placement relatively to the sleeve, a drum
revoluble on the sleeve and a helical spring
in the drum connected at its ends to the drum
and sleeve, said drum having ratchet teeth
concentric with the sleeve, and a manually
disengageable pawl normally engaged with
said teeth and carried by said handle struc-
ture, said element and drum having coactive
abutments adapted to resist rotation of the
drum relatively to said element when the
handle structure is rotated in the direction
in which the pawl clicks idly over said ratchet
teeth and formed to cam past each other when
said element is rotated in said direction under
engine power.

4. A portable starter mechanism for the
rotary element of an internal combustion
engine having as a fixed axial part of said
element a projecting shaft, said mechanism
comprising a handle structure having a sleeve
to fit over and revolve upon the shaft, a hollow
drum revoluble on the sleeve and con-
fined thereby against axial displacement
relatively thereto, a helical spring in the
drum connected at its ends to the drum and
sleeve, said drum having ratchet teeth con-
centric with the sleeve, and a pawl device
normally engaged with said teeth and man-
ually disengageable therefrom and carried by
said structure, said drum having means to
engage a portion of said element to prevent
rotation of the drum relatively to said ele-
ment when the handle structure is rotated in
the direction in which the pawl clicks idly
over said teeth and adapted to cam past said
portion of the drum when said element is
rotated in said direction under engine power.

In testimony whereof I affix my signature.
FREDERICK A. VASTANO.
